(57) **CLAIM**

The ornamental design for a bag, as shown and described.

DESCRIPTION

FIG. 1 is a front perspective view of a bag showing my new design;

FIG. 2 is the right side view thereof;

FIG. 3 is a back view thereof;

FIG. 4 is a left side view thereof;

FIG. 5 is a top view thereof;

FIG. 6 is a bottom view thereof; and,

FIG. 7 is a front view thereof.

The grayscale shading helps to illustrate surface contours and forms no part of the claimed design. The dashed broken lines and the halftone areas bounded by the dashed broken lines illustrate portions of the bag that form no part of the claimed design. The word mark "ETRO" and the Pegasus design mark are registered trademarks of Etro, S.p.A. that form no part of the claimed design. All surfaces not shown form no part of the claimed design.
